FIG. 1.

FIG. 2.

FIG. 3.

FIG. 4.

FIG. 1 is a top view of the cabinet;

FIG. 2 is a front view as seen from the bottom of FIG. 1;

FIG. 3 is an end view as seen from the right hand side of FIG. 1; and

FIG. 4 is a perspective view partly broken away and with the lids shown in raised position; the interior of the compartment shown on the left of this figure is that of a hollow cube with plane sides; the inverted U-shaped element on the upper front edge of the left-hand compartment terminates at each end where shown in this figure, i.e. at the side walls of such compartment; and the front support bracket for the perforated plate in the right-hand compartment extends across the full width of said plate similarly to the rear support bracket for such plate.

I claim:

The ornamental design for a combined cooking and warming cabinet, as shown and described.
